MACHINE AND METHOD FOR REPAIRING KNITTED FABRICS

Application filed April 23, 1929. Serial No. 357,426.

The invention relates to a machine and method for repairing knitted fabrics.

One object of the present invention is to provide a simple, practical and efficient machine of strong, durable and comparatively inexpensive construction designed to mend the runs in fabrics and particularly for mending the ladder-like runs in silk stockings and equipped with a power actuated needle and a manually operable form adapted to enable the silk stocking to be readily placed and properly held in position to be operated on by the needle and capable of enabling the stocking to be manually fed to the needle to cause the same to manipulate the successive threads of a ladder-like run and close the latter.

Another object of the present invention resides in the provision of a machine designed to mend runs in fabrics and equipped with means for manipulating the threads of a run in the fabric to close the run, and means to support the fabric in position to be operated on by the thread manipulating means, one of said means being operable in a predetermined definite position and the other means being arranged for movement at will by hand relative to the definitely positioned means, whereby the threads of the run may be operated upon successively to close the run.

A still further object of the present invention resides in a means or method for repairing runs in knitted fabrics through the instrumentality of a mechanically reciprocating needle adapted to operate through the run to manipulate the threads to close the run with the fabric supported on a form adapted to be fed at will by hand to the needle so as to present the threads of the run successively to the needle.

With these and other objects in view, the invention consists in the construction and novel combination and arrangement of parts hereinafter described, illustrated in the accompanying drawings, and set forth in the claims hereto appended, it being understood that various changes in the form, size, and minor details of construction, within the scope of the claims, may be resorted to with-

out departing from the spirit of the invention or sacrificing any of the advantages thereof.

In the drawings:—

Figure 1 is a vertical longitudinal sectional view of a machine for repairing knitted fabrics constructed in accordance with this invention. 55

Fig. 2 is a transverse sectional view of the same taken substantially on the line 2—2 of Fig. 1, parts being in elevation. 60

Fig. 3 is a front elevation of the machine.

Fig. 4 is horizontal sectional view of the machine.

Fig. 5 is an enlarged detail sectional view 65 of the stocking feeding means.

Fig. 6 is a detail sectional view illustrating the manner of mounting the eccentric roller.

In the accompanying drawings in which 70 is illustrated the preferred embodiment of the invention for mending stockings, the machine comprises in its construction a vertically reciprocating needle bar 1 mounted in a hollow head 2 of a tubular or hollow arm 3 of a supporting frame 4 which may be constructed of any suitable material and which is designed to be mounted upon a table or other suitable support (not shown) in any desired manner as will be readily understood. 75

The head 2 is provided at its top and bottom with vertically aligned guide openings 4' through which the needle bar slides and the latter is equipped at its lower end with a needle 5 detachably secured in a socket in the lower end of the needle bar by a set screw 6. In practice the head 2 will be of a sectional character to enable the parts to be readily assembled and the needle bar 1 is 80 provided within the hollow head with a horizontally projecting arm 7 which is engaged by a coiled spring 8 for yieldably moving the needle bar downwardly. The coiled spring 8 is arranged on an adjusting screw 9 and is interposed between the said arm 7 and the upper wall of the chamber of the hollow head. The screw which is threaded at the upper portion into the top of the head 95 at 10 is provided at its lower end with a 100

stop 11 preferably in the form of a head or collar and adapted to be set at the proper elevation by adjusting the screw to limit the downward movement of the needle 5.

5 The head 11 which is preferably secured on a reduced terminal portion of the screw by a pin 12 forms a stop or abutment for the arm 7 of the needle bar and the coil spring 8 permits the needle bar to be limited in its 10 downward movement.

The needle and needle bar are moved upwardly by means of a roller 13 mounted eccentrically on a head or collar 14 of a horizontal shaft 15 and engaging a horizontal 15 shoulder 16 preferably formed by the lower edge of a lug or enlargement 17 of the needle bar 1.

The enlargement 17 is preferably tapered upwardly as illustrated in Fig. 2 of the 20 drawings, but any other configuration may, of course, be employed, and the horizontal shoulder 16 against which the eccentric roller 13 abuts may be formed in any other desired manner. The collar or head 14 is mounted on one end of the horizontal shaft 15 which is journaled in suitable bearings 18 and 19 at the inner and outer portions of the upper holder arm 3 of the frame of the machine. The shaft 15 is provided at the 25 rear end with a combined hand and fly wheel 20 of the ordinary construction and adapted to be readily turned by hand to enable the operator to raise and lower the needle bar and the needle by hand in adjusting 30 the needle to the work.

The shaft also has mounted on it a grooved pulley 21 preferably formed integral with the hand or fly wheel 20 and receiving a belt 22 which extends to and is arranged on a grooved pulley 23 on the power shaft 24 of an electric motor 25 by means of which power is applied to the shaft 15 for rotating the same to reciprocate the needle bar vertically. When the shaft 15 is rotated, the eccentric roller 13 lifts the needle bar and the spring 8 moves the needle bar downwardly during the downward movement of the eccentric roller. By this construction the needle in its vertical reciprocation is positively moved upwardly and is yieldably moved downwardly. Any other suitable mechanism may, of course, be employed for actuating the needle bar and in practice the speed of the motor will be controlled by a suitable treadle-operated rheostat, so that the needle bar and needle will be reciprocated vertically at the desired speed.

60 The hand or fly wheel 20 and the grooved pulley 21 may be fixed to the end of the shaft 15 in any desired manner and instead of forming the grooved pulley 21 integral with the hand or fly wheel, any other suitable construction may, of course, be provided.

The electric motor 25 is suitably mounted on the frame of the machine at one side thereof as illustrated in Fig. 2 of the drawings, but it may be arranged in any other desired manner, as will be readily understood.

The needle is provided at its lower end with a hook 26 and it has a swinging latch 27 pivoted at 28 above the hook. When the pivoted latch 27 is open, it exposes the hook 26 and when the latch is closed, it covers the throat or opening leading into the hook and forms an eye. In practice, the last perfect loop of the fabric to be repaired is placed in the hook 26 and as the needle descends the said loop slides upwardly on the shank of the needle opening the latch and moving upwardly on the needle until the latch 27 is released. The latch, when thus released, drops by gravity and falls over the next cross thread in the broken fabric. The loop remains on the shank of the needle and as the needle rises the hook 26 catches the latch engaged thread, and the latch closes over the hook forming an eye encasing or enclosing and confining the second thread. This thread is then pulled up through the said loop, forming another loop, and this process is continued until all the cross threads are looped back into the fabric in substantially the same manner as repairing the fabric by hand. Any other suitable construction of needle may, of course, be employed.

During the said operation, the stocking is fed forward by hand to bring the cross threads successively in position to be operated on by the needle which reciprocates vertically through the run to be repaired and the stocking is supported on a manually operated substantially cylindrical form or holder composed of a pair of similar disks or cylindrical sections 29 arranged between spaced projecting side portions 30 of a lower approximately horizontal arm 31 of the frame of the machine. The arm 31 is preferably hollow, as shown, and is located below and spaced from the upper hollow arm 3 and the spaced side portions 30 project outwardly and upwardly at the end of the arm 31, as clearly illustrated in Fig. 1 of the drawings. The disks or sections 29 consist of outer peripheral portions, inner hub portions and connecting webs, as clearly illustrated in Fig. 2 of the drawings, and the hub portions are mounted on a transverse shaft 32 and on sleeves 33 of manually operable disks 34 arranged exteriorly of the spaced side portions 30 of the lower arm 31 of the frame and secured by screws 35 or other suitable means to the ends of the transverse shaft 32. The sleeves or tubular hub extensions 33 of the manually operable disks 34 extend inwardly from the inner faces of the disks 34 and are arranged in suitable bearing

openings 36 of the side portions 30 of the lower arm 31 and the said sleeves 36 form sockets to receive the end portions of the transverse shaft 32. The screws 35 are 5 threaded into the ends of the shaft 32 and the heads of the screws are preferably countersunk in the outer faces of the manually operable disks 34 and are arranged in flush relation with the outer faces of the said 10 disks.

The hub portions of the cylindrical sections 29 of the form or holder are counterbored at the outer portions of the hubs of the sections to receive the sleeves 33 and 15 the said sections 29, the shaft 32 and the manually operable disks or members 34 are rigidly connected together and rotate as a unit so that either one of the outer manually operable disks 34 may be rotated by the operator to feed the stocking to the needle to present the cross threads of a run successively to the said needle as required in the repair operation. The manually operable disks 34 which are preferably rounded and hollowed 20 out as shown, have knurled portions to enable them to be positively operated and securely held by the operator so that there will be no liability of the form or support slipping in the hand of the operator.

30 The sections 29 are provided at their inner sides with projecting hub portions 37 which space the web portions and peripheries of the sections from each other and providing an intervening space 40 for the passage of 35 the needle 5 to permit the needle to reciprocate through a run of a stocking arranged on and supported by the rotary manually operable form. The sections 29 of the form are flanged at their periphery or rim of the 40 required width and the rims are provided with transverse ribs 41 forming knurled or grooved portion for spacing the stitch. The grooving is to obtain additional gripping surface on the stocking between the form 45 wheel and the small feed roller. The knurled portion may be made of non-metallic material such as rubber to obtain the same result. The portion of the stocking to be repaired is laid on the rotary cylindrical 50 form at the upper portion thereof and the cross threads of the run to be repaired are placed on the gripping surface formed by the ribs 41.

In practice the stocking will be stretched 55 over the form and held by the hands of the operator at opposite sides of the form and the threads of the stocking will be maintained at the desired tension by the operator who simultaneously feeds the stocking to the 60 needle without releasing the grip of the hands upon the stocking. The machine, by this construction and arrangement and operation possesses all the advantages of a power operated machine and at the same 65 time permits the stocking to be manipulated

and stretched and fed by the hands of an expert operator to suit the requirements. This will enable all kinds of stockings from the most delicate web fabrics to the heavier thread fabrics to be repaired without liability of injuring the fabric by exerting too great a strain on the stocking. The groove or space between the sections of the cylindrical form for the passage of the needle forms a guide for enabling the operator to 70 accurately guide the ladder-like threads of the run to the needle. The stocking is held down against the form by a foot 42.

The foot is composed of side portions and a connecting shank or attaching portion 43 is carried by the front end of a lever 44 extending longitudinally of the lower arm 31 and mounted on a transverse pin or pivot 45 arranged at the inner end of the lower arm 31 of the frame and at a point intermediate of the ends of the lever 44. The lever 44 is composed of front and rear arms, the front arm extending forwardly and being located above the lower arm of the frame and extending upwardly from the pivot 45.

90 The shank 43 is secured to the front end of the lever 44 and the sides of the foot are spaced apart to provide an intervening space or opening 46 for the passage of the needle, the said side portions of the foot corresponding with the sections of the form for holding the stocking against the form while the threads are being manipulated by the needle. The front arm of the lever 44 also carries a corrugated feed roll 47 mounted on a 95 suitable pivot 48 and adapted to bear against the fabric in rear of the foot to cooperate with the form in feeding the stocking to pass the needle. The periphery of the feed roll 47 is provided with transverse ribs 49 corresponding with the ribs 41 of the sections of the form or holder and forming intervening grooves. The ribs of the feed roll cooperate with the ribs of the rotary form in feeding the fabric away from the needle as the run is repaired and the said feed roll cooperates with the foot in holding the fabric down on the rotary cylindrical form.

100 The rear arm of the lever 44 extends into the frame of the machine and the rear end of the lever is connected by a rod 49 with a suitable treadle, not shown, for enabling the foot and the feed roll to be readily lifted from the form when desired in adjusting the stocking on the form or for any other purpose during the repair operation and the said foot and feed roll, after being lifted from the form, are automatically returned to their engaging or operative position by a coiled spring 50 as soon as the treadle is 115 relieved of the pressure of the foot.

120 The coiled spring 50 is located above the rear arm of the lever 44 and is secured at its upper end to the frame of the machine preferably at the bottom of the bearing 130

and the lower end of the coiled spring is connected to the rear arm of the lever preferably at the point of attachment of the upper end of the rod 49.

5 The foot of the feed roll may be permanently held in an elevated position by means of the rotary cam 51 mounted on a shaft or pivot 52 and arranged to engage the rear arm of the lever 44 at the upper edge thereof. The shaft or pivot 52 extends from one side of the frame of the machine and has mounted on it an operating arm 53 adapted to be swung upwardly and downwardly by the operator to hold the foot and the feed roll elevated for a period of time and also to return the foot and the feed roll to their initial or operative position. The arm 53 may be arranged to cooperate with a stop 54 for limiting the movement of the arm in 10 one direction and in practice, the operating arm 53 will be swung upwardly and forwardly against the stop when it is desired to raise the feed roll and the foot from contact with the work permanently.

15 20 25 30 35 40 45 50 55 60 65 70 75 80 85 90 95 100 105 110 115 120 125 130

What is claimed is:—

1. A machine for mending runs in fabrics including a needle provided with means for manipulating the threads of a run to close the same, and manually operable means for feeding the fabric and feeding the threads of a run successively at will to the needle whereby to feed the fabric to the needle according to the gage of the fabric.

2. A machine for mending runs in fabrics including a needle provided with means for manipulating the threads of a run to close the latter, power actuated mechanism for operating the needle, and manually operable means for feeding the fabric at will by hand according to the gage of the fabric to successively present the threads of a run to the needle.

3. A machine for mending runs in fabrics including a needle provided with means for manipulating the threads of a run to close the latter, a movable support adapted to receive the fabric for supporting the same in position to be operated on by the needle, said support being manually operable by hand at will to feed the threads of a run successively to the needle according to the gage of the fabric.

4. A machine for mending runs in fabrics including a needle provided with means for manipulating the threads of a run for closing the same, mechanism for effecting a continuous operation of the needle, a movable support adapted to receive the fabric and provided with means for holding the threads of a run in spaced relation, and manually operable means operable at will by hand for moving the said support for feeding the threads by hand successively to the needle according to the gage of the fabric.

5. A machine for mending runs in fabrics

including a needle provided with means for manipulating the threads of a run to close the latter, a movable form adapted to receive the fabric and provided with transverse grooves adapted to form a gripping surface, and means for moving and manually operating the form for feeding the fabric by hand at will to the needle according to the gage of the fabric.

6. A machine for mending runs in fabrics including a needle provided with means for manipulating the threads of a run to close the latter, a pivotally mounted form arranged to receive the fabric and adapted to be rotated by hand at will to successively present the threads of a run to the needle according to the gage of the fabric.

7. A machine for mending runs in fabrics including a needle provided with means for manipulating the threads of a run for closing the latter, power actuated mechanism for continuously operating the needle, and a substantially cylindrical form adapted to receive and support the fabric beneath the needle, and manually rotatable at will to successively present the threads of a run to the needle according to the gage of the fabric.

8. A machine for mending runs in fabrics including a needle provided with means for manipulating the threads of a run to close the latter, power actuated mechanism for effecting a continuous operation of the needle, and manually operable means for supporting the fabric beneath the needle and for successively presenting the threads of a run to the needle, said means comprising pivotally mounted sections spaced apart to provide a passage way for the needle and adapted to be moved at will by hand according to the gage of the fabric.

9. A machine for mending runs in fabrics including a power actuated needle provided with means for manipulating the threads of a run for closing the latter, and a form arranged to support the fabric in position to be operated on by the needle and adapted to permit the fabric to be stretched over it and held by the hands of an operator at opposite sides of the form, said form including a movable member manually operable to feed the fabric at will by hand to the needle without the hands of the operator releasing their grip on the fabric.

10. A machine for mending runs in fabrics including a power actuated needle provided with means for manipulating the threads of a run for closing the latter, and a form arranged to support a fabric in position to be operated on by the needle and including a manually operable member having hand receiving means at opposite sides adapted to permit the operator to hold the fabric in a stretched condition and simultaneously feed the fabric at will by hand to the needle.

11. A machine for mending runs in fabrics including a power actuated needle provided with means for manipulating the threads of a run for closing the latter, and a form arranged to support a fabric in position to be operated on by the needle and provided at opposite sides with manually operable devices arranged to receive the hands of the operator to permit the operator to hold the fabric at opposite sides of the form in a stretched condition and simultaneously feed the fabric at will by hand to the needle without releasing the grip of the hands on the fabric. 70
12. A machine for mending runs in fabrics including a power actuated needle provided with means for manipulating the threads of a run for closing the latter, a form arranged to support a fabric in position to be operated on by the needle and including a member mounted for rotary movement and provided at opposite sides of the form with manually operable devices arranged to permit the fabric to be held in a stretched condition at opposite sides of the form by the hands of the operator and to simultaneously rotate the member to feed the fabric to the needle without releasing the grip of the hands on the same. 75
13. A machine for mending runs in fabrics including a power actuated needle provided with means for manipulating the threads of a run for closing the latter, and a form arranged to support a fabric in position to be operated on by the needle and including a substantially cylindrical support provided with a needle receiving groove and having operating means located at opposite sides of the form and arranged to receive the hands of the operator and permit the same to simultaneously hold the fabric in a stretched condition over the form and feed the fabric to the needle without releasing the grip on the fabric. 80
14. A machine for mending runs in fabrics including a power actuated needle provided with means for manipulating the threads of a run for closing the latter, and a form including a projecting arm having a movable member arranged to receive a stocking and provided with a needle receiving groove and having transverse thread receiving grooves at opposite sides thereof, said form being adapted to be grasped by the hands of the operator at opposite sides of it to enable a stocking to be held in a stretched condition simultaneously with a hand feeding of a stocking to the needle. 85
15. A machine for mending runs in fabrics including a power actuated needle provided with means for manipulating the threads of a run for closing the latter, and a form including a cylinder provided with a needle receiving groove and having thread receiving portions at opposite sides of the groove, and manually operable disk-like members located at opposite sides of the form and adapted to receive the hands of the operator, permitting the operator to hold the stocking in a stretched condition over the form and simultaneously feed the stocking at will by hand to the needle according to the gage of the fabric. 90
16. A machine for mending runs in fabrics including a power actuated needle provided with means for manipulating the threads of a run for closing the latter, an arm, a cylinder mounted in the arm and composed of sections arranged to form a needle receiving groove, a shaft extending across the arm and receiving the cylinder, and substantially disk-like members connected with the shaft at the ends thereof and located at opposite sides of the arm to permit a stocking to be held at opposite sides of the form in a stretched condition by the hand of the operator and to be simultaneously fed at will by hand to the needle without releasing the grip of the hands on the stocking. 95
17. A machine for mending runs in fabrics including a needle provided with means for manipulating the threads of a run to close the latter, stocking supporting means including an arm, having spaced side portions projecting outwardly and upwardly at the end of the arm, a shaft extending across the spaced portions of the arm, spaced rotatable members keyed to the shaft and located between the spaced portions of the arm and having hubs adapted to space the peripheries of said members apart to form a needle receiving groove, and substantially disk-like members connected with the ends of said shaft and having hubs to receive said shaft and by which the shaft is supported in the spaced portions of said arm, the peripheries of said spaced rotatable members having transverse ribs thereon for spacing the stitch of the fabric, whereby upon rotation of said disk-like members by hand the said shaft and the said rib rotatable members are rotated to feed the threads of the run at will successively to the needle. 100
18. A method of repairing runs in knitted fabrics consisting in supporting the fabric with the ladder-like threads of a run spaced apart, continuously reciprocating a needle at regular intervals and at uniform speed through the run to manipulate the threads thereof to close the run, holding the fabric by hand at opposite sides of the needle and tensioning the threads of the run and simultaneously feeding the fabric by hand at will to present the threads successively to the needle, according to the gage of the fabric. 105
19. A machine for mending runs in fabrics including means for manipulating the threads of a run to close the same, a movable 110
20. 25. 30. 35. 40. 45. 50. 55. 60. 65. 70. 75. 80. 85. 90. 95. 100. 105. 110. 115. 120. 125. 130.

form to receive the fabric for supporting the same in position to be operated on by said manipulating means, means for holding the fabric against the form, said form being operable by hand so as to feed the threads of the run successively to the needle at the will of the operator.

20. A machine for mending runs in fabrics including a needle provided with means for manipulating the threads of a run to close the latter, a movable form adapted to receive the fabric for supporting the same in position to be operated on by the needle, said movable form being provided with transverse grooves adapted to form a gripping surface, means for holding the fabric against the form, the form being manually operable by hand at will to feed the threads of the run successively to the needle.

21. A method of repairing runs in knitted fabrics consisting in supporting the fabric with the ladder-like threads of a run spaced apart, reciprocating a needle at regular intervals and at uniform speed through the run to manipulate the threads thereof to close the run, holding the fabric and tensioning the same by hand and simultaneously feeding the fabric at will by hand to present the threads of the run successively to the needle.

22. A method of repairing runs in knitted fabrics consisting in supporting the fabric on a form, mechanically reciprocating a needle through the run to manipulate the threads to close the run, and simultaneously tensioning the threads of the fabric and feeding the fabric at will by hand to present the threads of the run successively to the needle without changing the position of the fabric on the form.

23. A machine for mending runs in fabrics including a needle provided with means for manipulating the threads of a run to close the latter, the needle being located in a definite position for reciprocation, a movable form adapted to receive the fabric to support the same in position to be operated on by the needle, the form being manually operable by hand at will to feed the threads of the run successively to the needle.

24. A machine for mending runs in fabrics including means for manipulating the threads of a run to close the latter, means to support the fabric in position to be operated on by the aforesaid means, one of said means being operable in a predetermined definite position and the other means being movable at will by hand relative to the means located in definite position, whereby to present the threads of a run successively to the means for closing the run.

25. A method of repairing runs in knitted fabrics consisting in supporting the fabric on a movable form, mechanically reciprocating a needle through the run to manipulate

the threads to close the run and moving the form with the fabric on the form to feed the same at will by hand to present the threads of the run successively to the needle.

In testimony whereof I have hereunto set my hand, this 26th day of March, 1929.
